UNITED STATES PATENT OFFICE.

JOHN F. WRIGHT, OF STOCKTON, CALIFORNIA.

DESIGN FOR A BICYCLE PANTS-GUARD.

SPECIFICATION forming part of Design No. 30,501, dated April 4, 1899.

Application filed January 19, 1899. Serial No. 702,725. Term of patent 7 years.

To all whom it may concern.

Be it known that I, JOHN F. WRIGHT, a citizen of the United States, residing at Stockton, in the county of San Joaquin and State of California, have invented and produced a new and original Design for a Bicycle Pants-Guard, of which the following is a full, clear, and exact description, reference being had to the accompanying drawings, and to the figures of reference marked thereon, which form a part of this specification.

My invention relates to a new and original design for bicycle pants-guards adapted to partially or wholly encircle the leg of the wearer; and it consists chiefly in the configuration thereof and incidentally in its ornamentation, as will be hereinafter described and claimed.

In the drawings, Figure 1 is a rear elevation, and Fig. 2 is a side view, of my new design.

Similar figures of reference indicate corresponding parts.

My bicycle pants-guard is formed in the

general shape of an ellipse from band metal 25 by the irregular curves, as shown in Fig. 2, with one end 2 intersecting and extending beyond the line of the longitudinal diameter of the elliptical figure, said extended end 2 being the leading feature of the configuration 30 thereof. On the front side of the member 2 a raised portion or plate 3 is formed, which is adapted for any desired inscription thereon. The extreme ends 1 are slightly curved rearwardly, thus preventing the wear on the garment. 35

Having thus described my invention, what I claim as new, and desire to secure by Letters Patent, is—

The design for a bicycle pants-guard, as 40 herein shown and described.

In testimony whereof I affix my signature in presence of two witnesses.

JOHN F. WRIGHT.
